Edmundson

UNITED STATES PATENT OFFICE

EDWARD F. WHITE, OF RUTHERFORD, NEW JERSEY

COMBINATION FURNITURE SET

Application filed December 11, 1929. Serial No. 413,149.

This invention relates to furniture, more particularly to that type of furniture featuring a plurality of pieces of furniture, which, when assembled, represent a high chair, such as is used by infants.

Among the principal objects which the present invention has in view are: To provide means for holding a plurality of pieces of furniture together; to provide means whereby a plurality of pieces of furniture may be combined to form a child's high chair; to provide a set of miniature furniture when the high chair has been disassembled; to secure simplicity of construction, and to obtain other advantages and results as may be brought out in the following description.

In the drawing:

Figure 1 is a front elevation of a combined set of furniture, assembled to constitute a child's high chair.

Figure 2 is a side elevation looking at the right of Figure 1, and

Figure 3 is a sectional view taken on the line 3—3 of Figure 1, and showing a holding means for retaining the plurality of pieces in alignment.

In the specific embodiment of the invention illustrated in said drawing, and referring to Figures 1 and 2, the reference numeral 6 indicates a chair in general such as is used by a small child, said chair having a tray 4 slidably mounted to the upper arm rests of said chair, and a foot rest 5 suitably attached to a table within said chairs. Chairs of this type are usually constructed of a strong material, such as wood, but any other strong material may be used if desired. However, in this instance, the construction is preferably of wood, which will permit lightness of construction and easy manipulation.

Referring further to Figures 1 and 2, I have shown the chair 6, having the usual cross-bars or rungs 7 to brace the chair, so that the said chair will retain its original shape after being in use a length of time. Said cross-bars or rungs 7 are held to depending legs 8, and means are provided for holding the depending legs and the cross-bars or rungs securely together. Said means being in the form of mortises cut into the depending

legs, into which tenons on the cross-bars may be inserted, and then held securely in place by applying a glue or other retaining means. Seats 9 and 10 for the chairs and the table top 13 are retained in the depending legs in a like manner.

I have shown my invention in the drawing as one piece and representing a high chair. However, in assembling the various pieces to make up this high chair, I utilize an upper chair 11, a lower chair 12 and a table 13 having depending legs 14. It is necessary that the table 13 be first placed on the lower chair 12, the depending legs 14 resting on the seat 10 and means are provided for holding the table to the chair. The upper chair 11 is then applied to the lower chair 12, but above the table, the depending legs of the upper chair resting on the top of the legs 8 extending upwardly from the lower chair. In order to hold the chairs together, hooks 15 are provided, these hooks being shown as pivotally held by screws to the legs of the upper chair and hooked into eyelets 16, the eyelets projecting from the legs of the lower chair. When thus securely fastened, the set is of one piece and may be then used as a high chair, or placed in a remote corner of the room if so desired.

The legs 14 of the table 13 have rabbet grooves 17 which preferably extend the entire length of the legs. The said rabbet grooves act as the position holding means for retaining the upper and lower chairs from lateral displacement. The table 13 when inserted in place on the lower chair 12 is of slightly smaller size and will easily fit between the legs of the lower chair, and when so fitted, the table cannot be slid off. The square legs of the upper chair 11 may then be slid down the rabbet grooves of the table. The top of the table is then positioned under the seat of the upper chair, and the upwardly projecting legs of the lower chair meet the lower ends of the legs of the upper chair, as at 18, thereby completing the assembling of the three pieces. The hooks 15 are then securely fastened in place, and the chair 6 is ready for use.

The invention is of particular advantage

for use in an apartment where conditions will not permit excess furniture. Therefore, when a set of furniture comprising a plurality of pieces is combined into one piece, the said one piece can be placed in a corner of a room requiring minimum space. This set of furniture may be designed to match other articles of the room, thereby making it attractive as well as a necessity. In addition to the aforementioned, this set of furniture may be used indefinitely as a child having outgrown the high chair, the high chair may be then disassembled and the number of pieces which make up the high chair may then be used separately, as for instance for use of more than one child. In this instance, the combination set comprises two chairs and a table, although a third chair can be substituted in place of the table, if preferred.

20 I claim:

1. An article of furniture as characterized, comprising a first article of furniture having corner posts, a second article of furniture having corner posts spaced to agree with the spacing of the posts of said first article of furniture and superposed thereupon in substantial alinement therewith, and a third article of furniture having corner portions thereof interfitting with portions of the corner posts of the first article of furniture and projecting thereabove and interfitting with the contiguous superposed posts of the second article of furniture for retaining the third article of furniture within the confines of the other two and for retaining the superposed article of furniture against lateral displacement.

2. An article of furniture as characterized, comprising a first article of furniture having a seat and corner posts projecting above said seat, a second article of furniture having legs spaced to agree at their lower ends with the spacing of the upper ends of the posts of said first article of furniture and superposed

40 thereupon in substantial alinement therewith, and a third article of furniture having corner portions thereof interfitting with portions of the corner posts projecting above said seat of the first article of furniture and projecting thereabove and interfitting with the contiguous superposed legs of the second article of furniture, said third article of furniture resting upon the said seat of the first article of furniture and retained from displacement by said seat and posts, and said third article of furniture being retained against lateral displacement by engagement with the said corner portions of the third article of furniture, and hook means retaining the second article of furniture from longitudinal separation from the first article of furniture.

45 3. An article of furniture as characterized, comprising a first article of furniture having corner posts, a second article of furniture having corner posts spaced to agree with the spacing of the posts of said first article of furniture and superposed thereupon in sub-

stantial alinement therewith, and a third article of furniture having corner portions thereof interfitting with portions of the corner posts of the first article of furniture and projecting thereabove and interfitting with the contiguous superposed posts of the second article of furniture for retaining the third article of furniture within the confines of the other two and for retaining the superposed article of furniture against lateral displacement, and means for retaining the second article of furniture from longitudinal separation from the first article of furniture.

4. An article of furniture as characterized, comprising a first article of furniture having a seat and corner posts projecting above said seat, a second article of furniture having legs spaced to agree at their lower ends with the spacing of the upper ends of the posts of said first article of furniture and superposed thereupon in substantial alinement therewith, and a third article of furniture having corner portions thereof interfitting with portions of the corner posts projecting above said seat of the first article of furniture and projecting thereabove and interfitting with the contiguous superposed legs of the second article of furniture, said third article of furniture resting upon the said seat of the first article of furniture and retained from displacement by said seat and posts, and said third article of furniture being retained against lateral displacement by engagement with the said corner portions of the third article of furniture, and hook means retaining the second article of furniture from longitudinal separation from the first article of furniture.
